REFINING HYDROCARBON DISTILLATES

Chester E. Adams, Highland, and Theodore B. Tom, Hammond, Ind., assignors to Standard Oil Company, Chicago, Ill., a corporation of Indiana

No Drawing. Application November 20, 1944,
Serial No. 564,410

9 Claims. (Cl. 196—30)

1

This invention relates to the extraction of weakly acidic substances from hydrocarbon solutions and more particularly it relates to the extraction of mercaptans from hydrocarbon oils such as petroleum distillates, naptha, gasoline, kerosene, etc. In the manufacture of gasoline and other petroleum distillates known in refinery practice as "light oils," it has long been a problem to remove therefrom ill-smelling sulfur compounds which are primarily mercaptans. Certain processes such as the doctor treating process have been employed to convert mercaptans into other sulfur compounds such as disulfides which are less objectionable from the standpoint of odor. However, this conversion does not decrease the sulfur content of the gasoline and it has been found that the disulfides themselves are quite objectionable from the standpoint of gasoline detonation characteristics.

Numerous processes have been devised for extracting the mercaptans completely, thus producing a gasoline of higher knock rating and higher susceptibility to knock rating improvement resulting from the addition of tetraethyl lead. In general, these processes have employed strong alkali solutions in conjunction with certain mercaptan solubilizing agents known as solutizers.

One of the objects of this invention is to provide an improved solutizer for the extraction of weakly acidic substances from petroleum distillates. Another object of the invention is to provide a process of removing mercaptans more effectively from gasoline and other petroleum distillates by means of a solution which can be readily regenerated and recycled in the extraction operation. A further object of the invention is to provide a solutizer which is inexpensive and at the same time highly effective and which may be employed in combination with other solutizers.

According to our invention we employ as a solutizer in our process the alkali metal salts of the carboxy ethers having from 3 to 8 carbon atoms which we have discovered to be highly effective for the extraction of mercaptans occurring in light petroleum distillates, for example, straight-run or cracked gasoline, heavy naptha, etc. We have found that carboxy ethers having from 4 to 6 carbon atoms are especially effective. Typical examples of our solutizers are carboxy dimethyl ether, carboxy methylethylether, otherwise known as ethoxy acetic acid, carboxy diethyl ether, α , ω dicarboxy glycol dimethylether, etc. The carboxy ethers of this invention include primarily the alkoxy acids of which the acid radical

2

contains from 2 to 4 carbon atoms. In addition to ethoxy acetic acid mentioned above, we may employ particularly propoxy acetic acid and butoxy acetic acid. We may also employ the methyl and ethyl ethers of malic, lactic and tartaric acids. Other suitable ethers are the methyl and ethyl ethers of hydroxy valeric acid and anisic acid.

In carrying out our process, the hydrocarbon distillate containing mercaptans or other weakly acidic material is contacted preferably in a countercurrent extraction tower with a strong alkaline solution of the carboxy ether solutizer. For this purpose, sodium or potassium hydroxide may be used, preferably the latter, in a concentration of about 2 to 6 normal free caustic above that combined with the solutizer agent. The concentration of solutizer employed will usually be within the range of about 5 to 40 percent on the basis of free carboxy acid in the alkali solution. 15 Usually the carboxy ether concentration falls within the range of 1.5 to 4 molar. The extraction step is preferably carried out at ordinary temperature, for example 40 to 100° F., and the solutizer solution containing dissolved mercaptans or other weakly acidic substance is withdrawn from the extractor and separately regenerated after which it is recycled to the extraction step. The regeneration operation consists in removing from the caustic solutizer solution the 20 dissolved mercaptans or other weakly acidic substances, and is preferably carried out by blowing with air, for example at a slightly elevated temperature, e. g., 120 to 130° F. It is desirable to avoid subjecting the solutizer solution to a temperature sufficiently high to accelerate materially 25 hydrolysis of the carboxy ether employed.

In the regeneration operation, part of the mercaptans may be removed by dissociation and evaporation and part by the oxidizing action of the air converting them to disulfides which are no longer soluble in the solutizer solution. These disulfides may be removed as an upper oily layer and, if desired, a hydrocarbon solvent may be employed to assist in their removal from the regenerated solutizer solution. The solutizer solution is then recycled to the continuous extraction step of the process for the accumulation of more mercaptans.

The regeneration reaction may be accelerated 30 by employing catalysts which have the ability to speed the oxidation of the mercaptans. For this purpose certain alkali-soluble metal oxides may be employed, such as the oxides of lead, tin, etc. but we prefer to employ compounds of the character of phenols and polyphenols in accordance 35

with the teaching of the U. S. patent of Pevere, 2,015,038 (September 17, 1935). According to this method there is added to the solutizer solution a small amount of a phenol or polyphenol such as hydroquinone, catechol, pyrogallol, gallic acid, tannic acid, etc., using a concentration of about 0.1 to 1 percent, thereby greatly increasing the rate of regeneration in the presence of air or oxygen. One very significant benefit resulting from the use of these phenolic catalysts is that they enable regeneration to be carried out at a lower temperature, for example room temperature, thereby reducing hydrolysis of the carboxy ether solutizer which would occur, were the solution regenerated at substantially higher temperatures.

In the treatment of certain petroleum stocks, particularly cracked gasoline containing small amounts of phenolic compounds, especially cresols, it is desirable to precede the extraction with an alkali washing step to remove phenols, cresols, etc., thus preventing an excessive amount of such phenolic substances accumulating in the solutizer solution. In the treatment of such phenol-containing stocks, however, there is often a distinct advantage to permitting a controlled amount of such phenols, cresols, etc., accumulating in the solutizer solution, and we have found that the combination of cresols and our carboxy ethers provides a very effective reagent for extracting mercaptans. We prefer to control the amount of cresols in the range of about 1 to 3 normal concentration. Inasmuch as the distillate extracted by such a solution has been found to carry away in solution a small amount of cresols in the concentration which is in equilibrium with that in the solutizer solution, and inasmuch as cresols exert a valuable antioxidant effect on the treated gasoline, particularly in the case of cracked stocks, it is clearly desirable to employ a solutizer solution containing cresols. Other solutizers besides cresols may be employed with our carboxy ethers and a suitable proportion is a molar ratio of 0.2 to 0.8.

The following table gives the results obtained in the extraction of a sour naphtha containing primarily butyl mercaptan as an example of a weakly acidic substance. Removal of the butyl mercaptan is indicated by the copper number of the naphtha. Extraction was carried out in the ratio of one volume of solutizer solution to five volumes of naphtha in a single batch extraction step. The solutizer was ethoxy acetic acid, or isopropoxyacetic acid, alone or employed with cresol.

be seen from these data that excellent extraction of mercaptans was obtained in test 2 by the use of 3 normal potassium ethoxy acetate in 6 normal KOH solution and that the combination between ethoxy acetic acid and cresylic acid gave even more effective mercaptan extraction in tests 3 and 4. Isopropoxyacetate in test 8 was even more effective than the ethoxy compound in test 2. In a countercurrent operation it is easily possible to reduce the mercaptan concentration to a point at which the treated gasoline will react sweet to the doctor test. However, it may be more economical in practice to remove the major portion of the mercaptans from the stock by solutizer extraction and then treat the stock further in a separate sweetening operation with doctor, hypochlorite, etc., to produce a stock which will pass the doctor test where that is desired.

The copper number referred to above is determined by titrating a 100 ml. sample of naphtha with standard ammoniacal copper solution, 1 ml. of which is equivalent to 1 mg. mercaptan sulfur per 100 ml. (1 copper number). The end point is observed when the blue color fails to be discharged after shaking.

Having thus described our invention, what we claim is:

1. The process of extracting weakly acidic substances from hydrocarbon distillates which comprises contacting said distillates with an aqueous solution of an alkali metal hydroxide and a solutizer comprising an alkali metal salt of a carboxy ether containing from 3 to 8 carbon atoms.
2. The process of removing mercaptans from a petroleum distillate which comprises contacting said distillate with an aqueous solution of an alkali metal hydroxide and a solutizer comprising an alkali metal salt of a carboxy ether containing from 3 to 8 carbon atoms.
3. The process of claim 2 wherein said alkali metal is potassium.
4. The process of extracting weakly acidic substances from hydrocarbon distillates which comprises contacting said distillates with an aqueous solution of an alkali metal hydroxide and a solutizer comprising an alkali metal salt of an alkoxo acid containing from 3 to 8 carbon atoms.
5. The process of removing mercaptans from a hydrocarbon distillate which comprises extracting said distillate with an aqueous solution of an alkali metal hydroxide and a solutizer comprising a mixture of alkali metal cresylate and an alkali metal salt of a carboxy ether containing from 3 to 8 carbon atoms.

Test No.	Composition of solutizer solution	Copper number of naphtha		Butyl mercaptan distribution coefficient, Kq
		Before extraction	After extraction	
1-----	6N KOH, 2N EtOCH ₂ COOK	100	7	67
2-----	6N KOH, 3N EtOCH ₂ COOK ¹	100	4	120
3-----	4N KOH, N EtOCH ₂ COOK, 2N cresylate	100	2	245
4-----	4N KOH, 1.9N EtOCH ₂ COOK, N cresylate	100	2.5	195
5-----	3.6N KOH, 1.5N EtOCH ₂ COOK, 0.9N cresylate	100	5	95
6-----	4N NaOH, 2N EtOCH ₂ COONa, N cresylate	100	6	78
7-----	5N NaOH, 3N EtOCH ₂ COONa	100	6	78
8-----	4N KOH, 3N i-ProOCH ₂ COOK	100	3	162
9-----	5N KOH, 2N i-ProOCH ₂ COOK	100	3.5	138
10-----	4N KOH, 2N i-ProOCH ₂ COOK, N cresylate	100	2	245
11-----	3N NaOH, 2N i-ProOCH ₂ COONa, 1.5N cresylate	100	6	78

¹ The once-used solutizer was used again: copper No. 100 → 7.

The efficiency of extraction is indicated by the coefficient, Kq which is the concentration of mercaptans in the caustic solution divided by the concentration remaining in the naphtha. It will

75 6. The process of removing mercaptans from a sour hydrocarbon distillate which comprises extracting said distillate countercurrently with an aqueous solution of an alkali metal hydroxide

containing sufficient alkali metal salt of ethoxy acetic acid to increase substantially the solubility of said mercaptans in said solution.

7. The process of claim 5 wherein the concentration of free alkali metal hydroxide in the said solution is about 2 to 6 normal and the concentration of the said ethoxy acetic acid is about 1 to 4 normal.

8. The process of removing mercaptans from a sour hydrocarbon distillate which comprises extracting said distillate countercurrently with an aqueous solution of an alkali metal hydroxide

containing sufficient alkali metal salt of propoxy acetic acid to increase substantially the solubility of said mercaptans in said solution.

9. The process of removing mercaptans from a sour hydrocarbon distillate which comprises extracting said distillate countercurrently with an aqueous solution of an alkali metal hydroxide containing sufficient alkali metal salt of butoxy acetic acid to increase substantially the solubility of said mercaptans in said solution.
